UNITED STATES PATENT OFFICE.

JAMES A. ST. JOHN, OF ST. LOUIS, MISSOURI.

DESIGN FOR TYPE.

SPECIFICATION forming part of Design No. 13,557, dated January 30, 1863.

Application filed November 27, 1882. Term of patent 3½ years.

To all whom it may concern:

Be it known that I, JAMES A. ST. JOHN, a subject of the Queen of Great Britain, residing in the city of St. Louis, Missouri, have invented and produced a new and original Design for Movable Type, of which the following is a full, clear, and exact specification, reference being had to the accompanying impression, forming part thereof.

- 10 The following characteristics distinguish the present font of type: the condensed or vertically-elongated rectangular form of the various characters, the angular outline of the letters, numerals, and points, an outline of uniform width, and fineness of outline. The first of
- 15 the above-named characteristics has reference

to the general form of the entire space occupied by many of the letters—for instance, the letters B C D E G O S (upper case) and the letters a c e m n o, (lower case.) The other 20 characteristic—namely, a fine, uniform, angular outline—is observable in all the characters.

I claim—

The design for movable type herein shown and described, the same consisting in the vertically-elongated rectangular or condensed form, and the angular fine outline of uniform width.

JAMES A. ST. JOHN.
